Patented Oct. 18, 1966

206,014

SUPPORT PLATE FOR FLOWER STAND ASSEMBLY

Herbert M. Poston, 5434 Ridgecrest Road, Dallas, Tex.

Filed Mar. 15, 1965, Ser. No. 84,273

Term of patent 14 years

(Cl. D35—3)

FIG. 1

FIG. 2 is a side elevation of the support plate with the securing tabs in an alternate position.

The broken lines are shown for illustrative purposes only.

I claim:

The ornamental design for a support plate for flower stand assembly, as shown and described.
